UNITED STATES PATENT OFFICE.

MILON J. TRUMBLE, OF ALHAMBRA, CALIFORNIA, ASSIGNOR TO SHELL COMPANY, OF CALIFORNIA, A CORPORATION OF CALIFORNIA.

APPARATUS FOR TREATING HYDROCARBON OILS.

1,349,794.

Specification of Letters Patent. Patented Aug. 17, 1920.

Application filed July 19, 1916. Serial No. 110,080.

To all whom it may concern:

Be it known that I, MILON J. TRUMBLE, a citizen of the United States, residing at Alhambra, in the county of Los Angeles 5 and State of California, have invented a new and useful Apparatus for Treating Hydrocarbon Oils, of which the following is a specification.

My invention relates to the art of treating 10 hydrocarbon oils for the purpose of changing their physical characteristics. There exists in a natural state great quantities of hydro-carbon oil which are too heavy and viscous to be of any great commercial value. I 15 have found that by treating these oils in the manner hereinafter stated that they can be lightened in specific gravity and rendered less viscous. I also find that various products, such as gasolene, naphtha, benzin and 20 benzoltoluene can be produced from these heavy oils.

The principal object of my invention is to provide an apparatus of simple form and construction which will treat hydrocarbon 25 oils for the purposes above set forth.

Further objects and advantages will be made evident hereinafter.

Referring to the drawings, which are for 30 illustrative purposes only:

Figure 1 is a plan view of an apparatus embodying my invention.

Fig. 2 is an elevation, partly in cross section, on a plane corresponding to the line x^2-x^2 of Fig. 1.

In the apparatus shown, I provide a furnace 11, a first separator 12, a draft fan 13, a second separator 14, a third separator 15, a condenser 16, a fourth separator 17, a 35 first pump 18, and a second pump 19.

The furnace 11 consists of walls forming 40 a closed chamber 20 having a door 21 in the forward end thereof through which the air of combustion may be admitted and through which a gas or oil burner 22 projects, this burner being supplied with liquid 45 or gaseous fuel through a gas pipe 23. A checker-work 10, preferably formed of fire brick, is placed in such a position that the flame from the burner 22 plays against and 50 through it. Located in the bottom of the furnace 11 is a steam coil 24 which is fed at one end with water from a pipe 25 controlled by a valve 26, the other end of the steam coil being provided with a nozzle 27

through which superheated steam is injected 55 into the chamber 20.

The four separators are similar in construction in that each consists of an outer shell 30 having an inlet opening 31 in the top and having an outlet elbow 32 secured 60 to a conical bottom 33. Located inside each shell 30 are a plurality of cones 34, these cones being slightly smaller in diameter than the inside of the shell 30 and being secured to a central column 35 which is provided with a series of perforations 36 at a point directly under the cones 34. Each column 35 is connected through a series of vapor outlet pipes 37 with a vapor manifold 38. The chamber 20 communicates 65 with the interior of the first separator 12 through one of the openings 31 and the vapor manifold 38 of the first separator is connected by means of a pipe 40 with the intake side of the draft fan 13, this draft 70 fan being preferably a standard centrifugal fan driven by means of a pulley 41 from any source of power not shown. The pressure side of the fan 13 is connected through a pipe 42 with the opening 31 in the top of 75 the second separator 14. The vapor manifold 38 of the second separator 14 is connected through a pipe 43 with the opening 31 in the top of the third separator 15. The vapor manifold 38 of the third separator 15 80 is connected through a pipe 44 with the top of the condenser 16, this condenser being of any standard form and being water cooled by means of water admitted through a pipe 45 and taken off through a pipe 46. A portion of the water taken off through the pipe 46 passes through the pipe 47 and a valve 48 to a spray nozzle 49 located in the top of 85 the third separator 15. The bottom of the condenser 16 is connected through a pipe 50 with the opening 31 in the top of the fourth separator 17. Gage glasses 52 are provided 90 for each separator by means of which the level of any liquid in the bottom of the various separators may be determined.

An oil supply pipe 60 is provided, this pipe connecting into a fitting 61 in the top of which an oil injection pipe 62 is secured, this oil injection pipe discharging into the top of the first separator 12 just inside the 95 opening 31. A first separator residuum pipe 64 connects the outlet elbow 32 of the first separator 12 with the exhaust side of 100 105

the first pump 18, this pump being connected through a pipe 65 with one of the branches of the fitting 61. A second separator residuum pipe 66 connects the outlet 5 elbow 32 of the second separator 14 with the suction side of the second pump 19, the pressure side of the pump being connected through a pipe 67 with the fitting 61. A third separator residuum pipe 68 is provided, 10 this pipe being connected into the outlet elbow 32 of the third separator 15, the flow of fluid therethrough being controlled by a valve 69. A fourth separator residuum pipe 70 is provided being connected 15 into the outlet elbow 32 of the fourth separator 17, the flow of liquid therethrough being controlled by a valve 71. Located in the side of the third separator 15 is a heavy distillate supply pipe 80 which is provided 20 with a valve 81. The manifold 38 of the fourth separator 17 is connected through a pipe 90 with the suction side of a compressor 91, the pressure side of which is connected through a pipe 92 with a condenser or cooler 93 which is fed with cooling fluid through a pipe 94, this fluid being drawn off through a pipe 95.

The method of operation of my invention is as follows:

30 Oil under pressure is supplied through the pipe 60 from any source not shown. This oil may be ordinary crude oil, or it may be a residuum from previous distillations, or it may be any one of various 35 forms of hydrocarbon oil, being hereinafter called the raw material.

This raw material passes through the pipe 60, and the pipe 62 which discharge the oil on the top of the first separator 12. Gas or 40 oil being supplied to the burner 22 through the pipe 23, an intense combustion is produced in the chamber 20, the flame of this combustion playing against the checker-work 10 and on the steam coil 24 and producing steam from the water supplied 45 through the pipe 25, this steam being greatly superheated or even gasified before it passes out through the nozzle 27 into the chamber 20. The steam and the products of combustion unite to form a superheated gaseous 50 medium which may or may not contain some free oxygen. This gaseous medium passes downwardly through the opening 31 into the interior of the first separator 12 55 where it mixes with and acts upon the raw material which is injected therein by means of the spray nozzle 63. This mixture of raw material, hot gases, and steam, passes downwardly through the first separator 12. 60 The cones 34 tend to spread any liquid contained in the mixture over the inner wall of the separator 12 in a thin film, from which the gaseous constituents readily separate.

During the passage of the gaseous medium 65 and the oil through the separator 12

there occurs a very marked action on the body of raw material, the hot gases and steam mixing with the raw material and tending to alter the physical characteristics of the oil. Some of the oil is vaporized and 70 is carried out of the separator 12 with the other gases through the vapor outlet pipes 37, entering these pipes 37 through the perforations 36 in the column 35. That portion of the raw material which is not vaporized settles to the bottom of the first separator 12, being drawn outwardly through the pipe 64 by the first pump 18. This first pump 18 forces the residuum from 80 the first separator 12 upwardly through the oil injection pipe 62 to the spray nozzle 63 which is also fed with crude oil delivered by the oil supply pipe 60.

The mixture of hot gases and vapors of distillation leaving the first separator 12 85 through the vapor outlet pipes 37 passes into the vapor manifold 38 and is drawn through the pipe 40 by the draft fan 13, being forced through the pipe 42 into the second separator 14. In this separator the 90 gas and any liquid which may be contained therein is spread over the walls of the separator by the cones 34 and a further separation takes place, so that any free or condensed liquid which may be carried in the 95 vapors and gases is separated, falling to the bottom of the second separator 14 and being drawn therefrom through the second residuum pipe 66, the second pump 19 forcing this liquid through the pipe 67 into the fitting 61, in which it joins residuum from the first separator 12 and raw material from the oil supply pipe 60, the mixture being carried upwardly through the pipe 62 and delivered to the spray nozzle 63 in the top 100 of the first separator 12. The gases separated during the passage of the vapors through the second separator 14 are forced out through the small openings 36 in the column 35 and pass outwardly through the 105 vapor outlet pipes 37 into the vapor manifold 38. These vapors pass through the pipe 43 into the top of the third separator 15, where they are sprayed with water from the spray nozzle 49 for the purpose of removing certain of the solids and gases therefrom. The water is drawn out, either continuously or intermittently, as desired, through the pipe 68, heavy distillates being drawn off to storage through pipe 80. The 110 vapors are forced out through the perforations 36 in the column 35 into the vapor manifold 38 and are forced through the pipe 44 into the top of the condenser 16. The mixture of CO_2 and other gases, together 115 with the condensed liquids, all thoroughly cooled, passes through the pipe 50 into the fourth separator 17. In its passage through this separator, all the uncondensed gases are drawn off through the perforations 36 in 120 125 130

the column 35, and these gases may be allowed to exhaust directly into the open air through the exhaust pipes 87; the manifold 38, pipes 90 and 92, compressor 91, and condenser 93 being in that case omitted, or the vapors and gases may be compressed by the compressor 91 and cooled by the condenser 93 to remove certain volatile oils therefrom. The mixture of hydrocarbon liquids is drawn off through the pipe 70, this mixture of liquids containing a portion of the desired product.

It will be seen that my invention involves the conception of the treatment and retreatment of a hydrocarbon oil which is circulated through the first separator, this oil being treated by being intermittently mixed with superheated gases of combustion.

It will be seen that it further involves the recirculation of residuum from the second separator 14, and it involves the scrubbing of the mixture in the third separator 15.

It further involves the cooling of the mixture of gases and hydrocarbon vapors, and the separation of the condensed vapors to form the final products.

I claim as my invention:—

1. An apparatus for treating hydrocarbon oils comprising a furnace, means in said furnace for producing hot gases of practically uniform temperature, a separator having an opening in the top thereof, a flue for conducting the hot gases formed in the furnace to said opening, and an inlet pipe so arranged as to spray the oil to be treated through said opening in the direction of the hot gases.

2. An apparatus for treating hydrocarbon oils comprising a furnace, means for

causing a combustion in said furnace, a separator having an opening in the top thereof, a series of spreader cones in said separator so placed that the oil sprayed through said opening falls on the first of said cones and passes over the edge thereof intimately mixing with the hot gases, a vapor take-off for separator so arranged as to withdraw hot vapor from below said cones and conduct it outside said separator, a flue for conducting the hot gases formed by the combustion in said furnace to said opening, and an inlet pipe for spraying the oil to be treated through said opening.

3. An apparatus for treating hydrocarbon oils comprising a furnace, means for causing a combustion in said furnace, a separator having an opening in the top thereof, a flue for conducting the hot gases formed by the combustion in said furnace to said opening, an inlet pipe for spraying the oil to be treated through said opening, a pump, a pipe connecting the separator with the suction side of said pump, and a pipe connecting the pressure side of said pump with said inlet pipe.

4. An apparatus for treating hydrocarbon oils comprising a furnace, means in said furnace for producing hot gases, a separator having an opening in the top thereof, a flue for conducting the hot gases formed in the furnace to said opening, and an inlet pipe so arranged as to spray the oil to be treated through said opening in the direction of the hot gases.

In testimony whereof I have hereunto set my hand at Los Angeles, California, this 14th day of July, 1916.

MILON J. TRUMBLE.
